(57) **CLAIM**

The ornamental design for a valve for solution supply, as shown and described.

DESCRIPTION

FIG. 1 is a perspective view of the valve for solution supply of the present invention;

FIG. 2 is a front elevation view of the valve for solution supply of the present invention;

FIG. 3 is a rear elevation view of the valve for solution supply of the present invention;

FIG. 4 is a left side elevation view of the valve for solution supply of the present invention;

FIG. 5 is a right side elevation view of the valve for solution supply of the present invention;

FIG. 6 is a top plan view of the valve for solution supply of the present invention;

FIG. 7 is a bottom plan view of the valve for solution supply of the present invention; and,

FIG. 8 is an exploded perspective view, for reference, of the valve for solution supply of the present invention.

The broken lines shown in the drawings are included for the purpose of showing portions of the design that form no part of the claimed design.
